UNITED STATES PATENT OFFICE.

JOHN ROURKE, OF DENVER, COLORADO, ASSIGNOR OF ONE-HALF TO
AMOS C. GILTNER, OF SAME PLACE.

SMELTING OR REDUCING PLANT.

SPECIFICATION forming part of Letters Patent No. 484,942, dated October 25, 1892.

Application filed August 3, 1888. Serial No. 281,877. (No model.)

To all whom it may concern:

Be it known that I, JOHN ROURKE, a citizen of the United States of America, residing at Denver, in the county of Arapahoe and 5 State of Colorado, have invented certain new and useful Improvements in Smelting or Reducing Plants, of which the following is a specification, reference being had therein to the accompanying drawings.

10 My invention relates to an improved attachment for a smelting or reducing plant, said attachment consisting of condensing or depositing chambers connected with the main flue leading from the furnace of the plant.

15 The object of my improvement is to insure the saving of that part of the metal treated which is now carried off from the furnaces in the escaping smoke and vapors and to a great extent lost.

20 To this end the invention consists of the features, arrangements, and combinations hereinafter described and claimed.

In the drawings is illustrated an embodiment of the invention, in which drawings—

25 Figure 1 is a side elevation of one of my improved condensing-chambers. Fig. 2 is a longitudinal vertical section of a condensing-chamber, taken on the line *x x*, Figs. 3 and 4. Fig. 3 is a horizontal section taken on the 30 line *y y*, Fig. 2. Fig. 4 is a similar section taken on the line *v v*, Fig. 2. Fig. 5 is a vertical cross-section taken on the line *w w*, Figs. 3 and 4. Fig. 6 is a vertical section taken on the line *z z*, Fig. 5.

35 In the views let the reference-numeral 1 indicate the horizontal flue leading from the smelting-furnace (not shown) to a suitable stack. (Not shown.)

Let the numeral 6 designate a condensing 40 or depositing chamber connected with this main flue by means of a passage 5, provided with a damper, gate, or valve 8, so that communication between the main flue and the condensing-chamber may be entirely cut off 45 when necessary. In each passage 5 is also located a fan or other suitable air-blast mechanism 7. Each condensing or depositing chamber consists of two longitudinal side walls 9 9, the end walls, and roof. The 50 side walls are formed, mainly, of piers 10, so as to have as large amount of space for screen

as possible or as is consistent with the strength and security of the walls. The spaces between the piers 10 10 are filled with screens 13, each screen consisting of the double reticulated surfaces 13' 13', suitably framed. Such reticulated surfaces may be of wire-cloth of any suitable mesh, or they may be of wire stretched in one direction only, or of other suitable form, so long as their function is subserved— 60 namely, to retain between them any suitable fibrous material 15, which may be sponge, cotton, wool, hair, asbestos, mineral wool, or other material permitting the passage of air, gas, &c., yet straining therefrom solid particles. 65 The wires of surfaces 13' may be treated with boiled oil baked thereon or with any protecting covering or enamel, if it be deemed desirable to protect them against acid-fumes, &c. Such screens are so fastened to the sides 9 9 as to 70 cover the openings therein and so that the screens become, in fact, a large or even much the greater part of the sides.

In practice I prefer that the screens should not be flat; but in order to present a greater 75 surface to the outer air and to be in a position to be acted on by such air that they should be angled, as shown, these screens should be pivotally secured to the piers 10 by means of hinges B, so that they may be swung around 80 or opened or lifted from the piers at pleasure, as circumstances may require.

Where the chamber 6 is quite wide, the roof should be supported by a central line of supports 18, composed mainly of piers, so as to 85 interfere as little as possible with the circulation in the interior of the furnace. Each chamber is provided with a suitable floor, composed, preferably, of fire-tile or fire-brick material. Beneath this floor may be arranged a 90 number of small furnaces 32, having the customary grate-bars 33, dividing them into customary combustion-chambers and ash-pits, from which lead flues 34, beneath the flooring. These furnaces, for convenience of firing, 95 should open on the exterior of the chamber and their flues 34 should lead to some convenient stack for the discharge of the products of combustion and the maintenance of the necessary draft. In the drawings this 100 is accomplished by having the flues 34 lead to a longitudinal flue 35, communicating with

a stack 36. Inasmuch as the vapors and gases escaping from the chambers through the screens in the sides 9 9 might be detrimental to those obliged to work therearound and even 5 prevent them from so working, hoods 37 may be arranged over such screens, such hoods connecting with a flue or passage 38, leading to the main stack 36, a draft being created thereby under the hoods, taking off such gases 10 and leaving the air clear for a suitable height. These hoods are removably mounted on piers 10, so that they may be removed at pleasure. The operation as thus far described is as follows: The damper 8, controlling the communication from flue 2 to chamber 6, being 15 left open and the fan or blast mechanism 7 set in operation, the products of combustion passing through flue 2 are forced into the proper chamber 6. As in such chamber the current 20 from flue 2 spreads into a much larger space, the current loses much of its force, and some of the material brought over is deposited from this very cause. The vapors, smoke, &c., are also somewhat cooled and condensation of 25 part takes place with resultant deposition. As the only outlet for the vapors, smoke, &c., is through the screens, kept continuously cool by contact with the external air, condensation and deposition of the metallic elements 30 brought over are completed by such screens, only non-metallic gas, vapor, smoke, &c., succeeding in passing therethrough. After one chamber has been used sufficiently long its damper is closed and the damper of another 35 one opened. If it be desired to matte or to calcine further the matter deposited in the newly-cut-off chamber, fire is lighted in the furnaces 32. Before lighting the fires in these furnaces the hoods and screens should be re- 40 moved from sides 9 by lifting them from their

hinges and iron shutters 50 (see Figs. 1 and 3) placed in their stead, thereby converting the depositing-chamber practically into a smelting or reducing furnace for the time being, such convertibility adding largely to the efficiency of the chamber. 45

I am aware that it is not broadly new to pass smoke, fumes, &c., through a series of strainers of fibrous material for the saving of substances held in suspension thereby. Hence 50 such I do not claim; but

What I do claim is—

1. A condensing and depositing chamber having the outer side walls communicating with the external air and formed mainly of 55 screens, suitable supporting-piers between the screens, hoods covering said screens and also secured to the supporting-piers, and a flue with which said hoods are connected, said flue leading to a suitable stack, substantially as described. 60

2. A condensing and depositing chamber having its sides provided with a plurality of open spaces between supporting-piers, screens and metal shutters adapted to be removably 65 attached to the said piers, hoods covering said screens, furnaces underneath the floor of the said chamber, transverse flues leading therefrom, a longitudinal flue with which the transverse flues are connected, and a suitable 70 stack connected with the top of the said hoods and into which the longitudinal flue opens, substantially as described.

In testimony whereof I affix my signature in presence of two witnesses.

JOHN ROURKE.
